UNITED STATES PATENT OFFICE.

HENRY S. HOPPER, OF DETROIT, MICHIGAN.

COTTON-PICKER.

1,111,797.

Specification of Letters Patent. Patented Sept. 29, 1914.

Application filed October 13, 1913. Serial No. 794,962.

To all whom it may concern:

Be it known that I, HENRY S. HOPPER, a citizen of the United States of America, residing at Detroit, in the county of Wayne and State of Michigan, have invented certain new and useful Improvements in Cotton-Pickers, of which the following is a specification, reference being had therein to the accompanying drawings.

10 The invention relates to devices for assisting in the picking of cotton, and it is the object of the invention to obtain a hand-operated tool which will enable the operator, when standing in an upright position, 15 to pick the cotton from all portions of the plant.

It is a further object to obtain a simple construction of operating mechanism and one which is easily manipulated in all positions of adjustment.

In the drawings: Figure 1 is a longitudinal vertical section through the picker; Fig. 2 is a longitudinal horizontal section thereof; Fig. 3 is an end elevation, partly in section; and Fig. 4 is a perspective view. Fig. 5 is a sectional view of the clutch mechanism taken on the line $x-x$ of Fig. 3.

In the usual operation of picking cotton it is necessary for the workman to stoop to obtain access to many of the bolls upon the plant, while other bolls can be reached only in upright position. As a consequence the fatigue of the operation is occasioned by the constant change in position required instead of the act of removing the cotton locks from the bolls.

With my improved construction I have provided a hand-operated and directed instrument which may be manipulated by the operator while standing in upright position and which is capable of reaching all parts of the plant. This consists essentially of an arm or extended member preferably strapped or otherwise secured to the operator's arm and directed thereby. This extended arm is provided with a conduit through which the cotton is conveyed and a picker mechanism which is actuated by the free hand of the operator. Furthermore, the means employed for operating this picker mechanism is such that in all positions of the instrument it may be actuated with equal facility.

In detail, A is the extension arm which is formed to provide a conduit B through which the cotton is conveyed and a return

conduit C for the endless conveyer chain D. This chain is formed with projecting picking points E, which in the rotation of the chain and at the free end of the arm 60 may be engaged with the cotton boll, so as to disengage the locks and carry the same into the conduit B. The chain travels upon sprockets or pulleys F and G respectively at the outer and inner ends of the arm, 65 which are so arranged that the inwardly-moving portion of the chain travels through the conduit B and the outwardly-moving portion through the conduit C. At the inner end of the arm is a discharge tube H 70 which leads to the receptacle carried by the operator for receiving the cotton. To disengage the cotton locks from the picker points E of the carrier, a rotating wheel or doffer I is arranged at the bend between the conduit B and the discharge tube H, this wheel being provided with a series of projecting tines J for disengaging the cotton from the points. A further means of disengagement 75 which also prevents the winding of the cotton upon the wheels I, consists of curved guide-bars K arranged between the tines J and acting as strippers.

As it is necessary to bend the arm A at various angles and in various directions, a 80 crank or similar operating device could not be conveniently manipulated. I have therefore provided a flexible operating connection which is manipulated by pulling. This, as shown, consists of two cords L and L' 85 passing over grooved pulleys M and M' respectively and then connected with spring or other counter-pulling device N. Both cords are pulled in the same direction at the same time. The direction of movement 90 of one cord over one pulley and the other under the other pulley is such that the pulleys will be rotated in opposite directions and will be reversed upon the return of the cords by the spring N. The pulleys M M' 95 are mounted upon the shaft O and each is connected therewith by a clutch P which operates only in one direction. Thus the shaft will be driven by one of the pulleys when the cords L L' are being drawn outward, and by the other pulley when the cords are returned by the force of the spring N, the movement of the shaft being always 100 in the same direction.

The doffer wheel I is directly mounted 110 upon the shaft O and the chain D is driven through the medium of a belt-and-pulley

connection Q between said shaft O and the shaft G' for the sprocket G.

In operation, the operator may move from plant to plant and direct the picker successively to the bolls upon different portions of each plant. At the same time the cord L is drawn outward and returned by the operation of the free arm and hand, and will thereby impart rotary movement to the shaft 10 O. This, in turn, will rotate the doffer wheel, and through the medium of the belt-and-pulley connection Q will operate the sprocket G and drive the chain D. The movement of the chain D will cause the 15 pickers to remove the cotton locks from the bolls and to carry them up through the conduit. At the inner end of this conduit the doffer wheel will operate to disengage the locks from the picker teeth, permitting the 20 latter to return with the portion of the chain passing through the conduit C. The doffer wheel carries the cotton to the tube H, through which it is discharged into the bag or receptacle for receiving the same. Dis- 25 engagement of the cotton locks from the doffer tines is accomplished by the curved guide bars K, which are fashioned to gradually strip the cotton from the tines. The outer ends of these stripper bars are free, 30 which permits any cotton wedging between the same to be pushed off their ends.

The arm A may be attached through the medium of a strap R to the upper part of the operator's forearm and may also be 35 grasped by the hand at a lower point.

What I claim as my invention is:

1. A picker, comprising an extended arm attachable to and directable by one arm of the operator, said extended arm providing a conduit, an endless conveyer chain movable inwardly through said conduit, picker points carried by said chain, a revolute actuating member for said chain, and a flexible connection engaging said actuating member to 45 operate the same and adapted for actuation by the free hand of the operator.

2. A picker, comprising an extended arm, said extended arm providing a conduit, an endless conveyer chain passing through said

conduit, picker points on said conveyer 50 chain, a revolute shaft for actuating said conveyer chain, a pulley, a flexible connection passing over said pulley, and a clutch between said pulley and revolute shaft for actuating the same in one direction. 55

3. A picker, comprising an extended arm, said extended arm providing a conduit, a conveyer chain extending through said conduit, picker points on said chain, a discharge tube at the inner end of said conduit, a revolute tined wheel for disengaging the cotton locks from said picker, mechanism for simultaneously operating said chain and tined member, and a flexible connection for operating said mechanism adapted for manipulation by the free hand of the operator. 60 65

4. A picker, comprising an extended arm, said extended arm providing a conduit, a conveyer chain in said conduit, picker points on said conveyer chain, a discharge tube at 70 the inner end of said conduit, a tined rotary member for disengaging the bolls from said chain and delivering the same into said discharge tube, mechanism for operating said chain and tined member, a flexible actuating 75 connection, a pair of pulleys over which said flexible connection passes, a spring for returning the flexible connection, and clutches for imparting driving movement from said pulleys to said mechanism respectively in 80 the outward and return movement of said flexible connection. 85

5. A picker, comprising an extended arm, said extended arm providing a conduit, a conveyer chain passing through said conduit, picker points upon said chain, a discharge tube at the upper end of said conduit, a revolute tined doffer wheel for disengaging the cotton locks from the picker points, and strippers between said tines for 90 disengaging the cotton therefrom, the ends of said strippers being free. 95

In testimony whereof I affix my signature in presence of two witnesses.

HENRY S. HOPPER.
